US0D1111087S

(12) **United States Design Patent** (10) **Patent No.:** **US D1,111,087 S**
(45) **Date of Patent:** **** Feb. 3, 2026**

(54) **ELECTRONIC DEVICE**

(71) Applicant: **Block, Inc.**, Oakland, CA (US)

(72) Inventors: **Yenliang Chen**, San Francisco, CA (US); **Rowan Schultz**, San Francisco, CA (US); **Michael MacLennan**, Oakland, CA (US)

(73) Assignee: **Block, Inc.**, Oakland, CA (US)

(**) Term: **15 Years**

(21) Appl. No.: **29/956,036**

(22) Filed: **Aug. 5, 2024**

Related U.S. Application Data

(63) Continuation of application No. 29/820,537, filed on Dec. 22, 2021, now Pat. No. Des. 1,042,615.

CLAIM

The ornamental design for an electronic device, as shown and described.

DESCRIPTION

FIG. 1 is a top, front, right-side perspective view of an electronic device;

FIG. 2 is a top, front, left-side perspective view thereof;

FIG. 3 is a top, back, right-side view thereof;

FIG. 4 is a top, back, left-side view thereof;

FIG. 5 is a front view thereof;

FIG. 6 is a back view thereof;

FIG. 7 is a left-side view thereof;

FIG. 8 is a right-side view thereof;

FIG. 9 is a top view thereof; and,

FIG. 10 is a bottom view thereof.

The dashed broken lines depict portions of the electronic device that form no part of the claimed design. The dot-dashed broken lines represent boundaries of the claimed electronic device and form no part of the claimed design.

1 Claim, 10 Drawing Sheets
